UNITED STATES PATENT OFFICE.

STEPHEN B. PHELPS, OF PITTSBURGH, PENNSYLVANIA.

DOWEL PIN AND CUP FOR MOUNTING PATTERNS.

Application filed May 4, 1922. Serial No. 558,386.

To all whom it may concern:

Be it known that I, STEPHEN B. PHELPS, a citizen of the United States, and a resident of Pittsburgh, in the county of Allegheny and State of Pennsylvania, have invented a new and Improved Dowel Pin and Cup for Mounting Patterns, of which the following is a description.

My invention relates to a dowel pin and cup adapted to be secured respectively to a half pattern and to a pattern board, and arranged for centering the pattern on the board.

The general object of the invention is to provide an improved means for the indicated purpose promoting facility and saving time in the placing and accurate centering of the half pattern.

The nature of the invention and its distinguishing features and advantages will clearly appear as the description proceeds.

Reference is to be had to the accompanying drawings forming a part of this specification, it being understood that the drawings are merely illustrative of practical examples of the invention.

Figure 1 is a plan view of a pattern board equipped with my improved sockets;

Figure 2 is an under side view of a half pattern provided with dowel pins to engage the sockets in the pattern board;

Figure 3 is a cross section of the half-pattern in position on the pattern board, the view indicating in dotted lines the molding flask;

Figure 4 is an elevation of a dowel pin in slightly modified form, a fragment of the pattern being in section;

Figure 5 is a vertical section of the pattern board and my improved pin socket;

Figure 6 is a vertical section showing a fragment of the pattern and a further modification of the pin;

Figure 7 is a vertical section through a portion of the pattern board and a modification of my improved cups;

Figure 8 is a plan view of the cup shown in Figure 7.

It will be understood that my improved dowel pins and cups are adapted for use in centering patterns of various kinds. I have shown in Figure 1 an ordinary pattern board A having my improved cup 10 secured by pins 11, the number and arrangement of the cups being adapted for the dowels on a half pattern B for molding a pipe section, said

pattern B having dowel pins comprising shanks 12 and blocks 13. In Figure 3 the shank 12 is shown in the form of a screw. In Figure 4 the shank, (15) securing the block 16 to the half pattern B is shown as a nail passing through the bore of the block the same as the screw 12. The block 16 has the edge rounded as at 18, Figure 4.

Cups 10 are secured by a nail 11, or screw, or the like passing through the bottom of the cup centrally thereof and into the material of the pattern board A. The edge 17 of the cup is bevelled to facilitate the entrance of the pin block 16.

In Figure 6 the pin is in the form of a cup-like shell 19 driven with its open end into the material of the half pattern here indicated by the letter C. The said shell and the cup hereinafter referred to are formed with crimps 20.

In Figure 7 is shown a cup 21 to receive the pin 16, said cup fitting in a corresponding recess in the pattern board D. The crimps 20 are produced in a manner that the pins 19 and cups 21 present exteriorly angular parallel ribs so that the pins and cups may be driven into the pattern and pattern board respectively for solidly holding the pins and cups in place to prevent turning.

The device takes the place of wooden and other dowels now in use and has an advantage that it retains its form and size permanently so that the pattern is prevented from shifting by looseness between the dowel and cup. A great advantage of the device also is that it can be used to mount patterns on boards to permit orders for only one casting, thereby saving cost owing to the slight expense of screwing two or three dowels to the half pattern or patterns, in accordance with my invention, whereas with the common method of mounting patterns the cost is too great to leave a saving even though several castings are to be made on the one order. A further great value of the described device is that it saves expense of making complete patterns when they are symmetrical, as only half a pattern is used by casting with patterns secured by the cups and pins described.

Even in instances where the pattern is not symmetrical, it is often possible owing to my invention to make the unsymmetrical part loose and move it onto the pattern board, thus saving approximately half the pattern costs. Again, the proper use of core prints

and cores permits numerous irregular patterns to be made with only half a pattern and effect a saving in some instances of large amounts of money in the construction 5 of even single patterns. The method of casting with my improved dowel pins and cups also saves the cost of making a pattern board for those patterns on which orders are 10 large enough that would even warrant expensive patterns, for with the foundry equipped with pattern boards the half pattern only needs to be made and the dowels screwed or otherwise fastened into place thereon. One pattern board can be used 15 for several sizes of flasks by inserting more or less wear plates in the board to correspond with the pin holes in the flask. An important advantage also is that the improvement permits unskilled labor at low wage cost to 20 make the molds of molding machines and with a great saving in time over the hand methods and where skilled molders are necessary for floor molding. The invention permits also the mounting of patterns on boards 25 of very large patterns which are above the capacity of the usual machines or available in most shops. A saving is also effected over the "bedding in" methods of molding as well as the costs in patterns. It will be understood 30 that a great variety of patterns may be placed on pattern boards the limit being the size only of the flask that is used. Unsymmetrical patterns made in halves can be mounted with both halves on a pattern board 35 and thus two castings can be made practi-

cally in the usual time it takes for making one on a machine, the dowels in this case being screwed into each half pattern to match the suitably located dowel cups set in the boards.

I would state in conclusion that while the illustrated examples constitute practical embodiments of my invention, I do not limit myself strictly to the exact details herein illustrated, since, manifestly, the same can be considerably varied without departure from the spirit of the invention as defined in the appended claims.

Having thus described my invention, I claim:

1. A pattern holder for use in foundries comprising a cup-shaped body adapted for the reception of a dowel pin and having a bottom wall provided with a centrally arranged opening, and a fastening member adapted to extend through said opening for securing the cup-shaped body in position.
2. In a pattern holder for use in foundries, the combination with a pin of cylindrical formation having a longitudinal opening extending entirely therethrough, of a cup to receive said pin and having a bottom wall provided with a longitudinal opening, and separate fastening members extending through said openings for securing the pin and the cup in position.
3. The construction set forth in claim 2, said cup being exteriorly smooth.

STEPHEN B. PHELPS.
